UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING MACHINE.

Application filed June 16, 1926. Serial No. 116,285.

This invention relates to sewing machines of that known type which are constructed with a needle operating to penetrate the work from above and two loopers and loop-spreading means situated beneath the work and acting to take and spread the loops of needle thread that are presented by the needle and to position each loop so that upon the next penetrating thrust of the needle 10 the latter will enter the spread loop.

Some sewing machines of this type, especially those adapted to form stitches along the edges of a buttonhole or around an eyelet, are provided with a turret on which the 15 loopers and loop spreaders are mounted, the turret being constructed to turn in order to carry the stitching around the ends of the buttonhole or around the eyelet. As illustrating a sewing machine of this type reference may be made to United States 20 Patents No. 862,238, August 6th, 1907 and No. 911,551, February 2nd, 1909. In this type of sewing machine the loopers are usually given a more or less irregular oscillatory movement and the present invention 25 relates to a novel means for producing such an oscillating movement of the loopers, which means is conducive to high speed operation.

In accordance with the invention the loopers and loop spreaders are operated by a cam which is situated beneath the turret and which is geared to the sewing shaft. By placing the cam device in this position the 30 only parts which are subjected to the irregular motion are the connections from the cam device to the looper and loop spreaders and as these connections are relatively light they can be given the desired irregular motion at a speed without producing any undesirable jar or vibration.

In order to give an understanding of the invention I have illustrated in the drawings a selected embodiment thereof which will 45 now be described after which the novel features will be pointed out in the appended claims.

Fig. 1 is a side view of a sewing machine embodying my invention with the cover 50 plate removed;

Fig. 2 is a fragmentary view partly in section showing the turret with the loopers and loop spreaders thereon and also illus-

trating the cam device for operating the looper and loop spreaders; 55

Fig. 3 is a section on substantially the line 3—3, Fig. 2;

Fig. 4 is a section on substantially the line 4—4, Fig. 2;

Fig. 5 is a section on the line 5—5, Fig. 2; 60

Fig. 6 is a section on the line 6—6, Fig. 3;

Fig. 7 is a section on the line 7—7, Fig. 3.

In the drawings 1 indicates the bed frame of a sewing machine on which is mounted the usual head 2, the latter having mounted therein the usual vertically-reciprocating needle bar 3 which carries the needle 4 that penetrates the work from above, the work being held in the usual work clamps 5. The needle bar 3 is actuated from a driving 70 or sewing shaft 6 by any suitable or usual mechanism (not shown).

The loopers which co-operate with the needle in concatenating the thread are situated beneath the bed plate 1 and are mounted on a turret 7 as usual in sewing machines of this type, said turret being supported in suitable bearings 8 and being rotatable about a vertical axis so as to carry the stitching around the ends of the buttonhole or around the eyelet. The turret is turned in the usual way through the medium of a vertically-arranged rock shaft 9 which is provided at its lower end with a gear sector 10, the teeth of which mesh with a gear 11 formed on the 75 turret. This rock shaft also rotates the needle bar synchronously with the turret, this being accomplished by another gear sector 12 fast on the rock shaft which meshes with a gear 13 carried by the needle bar mechanism. 80

The rock shaft 9 is turned through the medium of a main cam, not shown, which is situated in the cam housing 14, this being a common and usual construction in sewing machines of this type, it being understood that the turret will make a half rotation at each end of the buttonhole. 85

The turret 7 carries the usual throat plate 15 having a sewing opening therethrough through which the needle operates. 90

The two loopers which co-operate with the needle are shown at 16 and 17 respectively, each looper having associated with it a loop spreader for spreading the loop of 105 needle thread. These loop spreaders are in-

- 2
- dicated at 18 and 19 respectively. The two loops 16 and 17 are of usual construction and are carried by an oscillatory looper carrier 20 in the form of a block pivoted to the 5 turret at 21, the oscillation of the looper carrier causing first one looper and then the other to take a loop of needle thread and hold said loop in position to receive the needle on the next penetrating thrust.
- 10 The loop spreaders 18 and 19 are pivotally mounted on the looper carrier 20 as usual in devices of this type, each spreader having a shank 22 which is journalled in a bearing on the looper carrier. Each 15 spreader is acted on by a spring 23 which normally tends to hold it in alignment with the looper. Each spreader is swung away from the corresponding looper to spread the loop of needle thread by means of a spreader 20 actuator 24 which is also pivoted on the turret co-axially with the looper carrier and is provided with two arms 25 that co-operate with the tails of the spreaders to give them their spreading movement.
- 25 The parts thus far described are or may be all as usual in buttonhole sewing machines of this type and their operation will be readily understood by reference to the above-mentioned patents.
- 30 As stated above the present invention relates to novel means for giving the looper carrier 20 and the spreader actuator 24 their oscillating movements. According to the present invention these parts receive their 35 oscillations from a cam member 26 which is situated beneath the turret and is mounted on a horizontal shaft 27 that is driven from the shaft 6. The shaft 27 is journalled in suitable bearings 28 and 29 which are carried by bearing brackets 290 and 291, and said shaft has thereon a bevelled gear 30 which meshes with a bevelled gear 31 on a vertical shaft 32, said shaft having on its upper end a bevelled gear 33 which meshes 40 with and is driven by a bevelled gear 34 carried by the sewing shaft 6. The lower end of the vertical shaft 32 is shown as journalled in suitable bearings 35 carried by the bearing bracket 290. The cam member 26 is thus geared to the sewing shaft 6 so that it rotates in timed relation therewith. This cam member 26 has on one face a cam groove 36 by which the looper carrier 20 is actuated and on its other face a cam groove 45 55 37 by which the spreader actuator is actuated.
- The looper carrier has rigid therewith an arm 38 to the end of which is pivotally connected a vertically-extending connection 39, the latter having a shank portion 40 that extends through an axial bore 41 formed on the turret. This shank 40 is connected at its lower end to a cam-actuated arm 42 that is pivoted to the frame at 43, 60 65 said arm having a lateral projection 44 car-

rying a roll 45 that is received in the cam groove 36.

As the cam 26 rotates, therefore, the arm 42 is swung up and down and such up and down movement operates through the connection 39 and arm 38 to oscillate the looper carrier 20. Inasmuch as the turret with the looper carrier has a turning motion I have employed a ball-and-socket connection between the shank 40 and the arm 42 to allow for such turning motion, such ball-and-socket connection being situated in the axial line of the turret.

The end of the shank 40 is shown as having a ball 46 which is received in a socket 47, the latter being formed partially in the end of the arm 42 and partially in a removable cap 48 secured to the arm. As this ball-and-socket connection is in the axial line of the turret, the turning movement of the latter will in no wise effect the operation of the device.

As stated above the spreader actuator 24 is actuated by the cam groove 37 in the cam device 26 and for this purpose said spreader actuator is provided with an arm 49 to which is connected a link or connection 50, the latter extending down through the axial opening 41 of the turret and also through an opening 51 formed in the ball 46 as shown in Figs. 6 and 7. The lower end of this connection 50 is provided with a ball 52 which is received in a socket 53 formed partially in the end of an arm 54 and partially in a cap 55 which is removably secured to the arm. The arm 54 is one arm of a forked member 56 which is pivotally mounted on a stud 57 carried by the frame. This forked member 56 embraces the cam 26 and the other arm 58 thereof extends in the rear of the cam device and is provided with a roll 59 which enters and operates in the cam groove 37. With this construction the cam groove 37 will operate to swing the forked arm 56 up and down and such movement will be communicated through the connection 50 to the looper spreader thereby giving it its required movement.

The ball-and-socket connection 52, 53, is situated in the axial line of the turret and thus the rotating movement of the turret and consequent rotating movement of the connection 50 will not effect the operation of the device.

The cam 26 is preferably adjustably secured to the shaft 27 so that it may be adjusted to bring the action of the loopers into proper timed relation with the action of the needle. For this purpose the cam is loosely mounted on the shaft 27 and is adjustably secured to a collar 60 which is rigid with said shaft. This collar 60 is received in a recess 61 formed in one face of the cam and the cam is connected to the collar by means of screws 62 which screw into the collar

and extend through a slot 63 formed in the cam. By loosening the screws 62 the cam may be turned relative to the shaft 27 thereby to bring it into proper timed relation with the needle and when the proper adjustment has been made and the screws 62 tightened the cam will be retained in its adjusted position.

In order to give the loopers their proper movement the cam groove 36 is more or less irregular. With the construction herein shown the cam-actuated parts which have the irregular movement are simply those between the arm 42 and the looper carrier. These parts are relatively light and can, therefore, be given the required irregular motion at a high speed without subjecting the parts to undue strain or produce undesirable jar or vibration. The same is also true of the parts by which the looper spreader is actuated.

The connection 39, 40 for operating the looper carrier is preferably made adjustable as to its length so as to provide for bodily adjustment of the looper carrier. As shown the member 39 is provided at its lower end with a hub through which the upper end of the shank 40 extends, the hub being adjustable vertically on the shaft and held in adjusted position by the screw 72. The connection 50 is also preferably adjustable and for this purpose it is made in two parts, an upper tubular part 73 and a lower stem 74. The upper end of the stem 25 telescopes into the lower end of the tubular part 73 and the two are secured together in adjustable positions by screws 75.

70 and 71 designate thread guides for the lower thread t in case a lower thread is used. 70 is an arm having a guide eye situated in the axial line of the turret and 71 is a thread-guiding tube carried by the turret and through which the thread extends and by which it is protected as the turret turns about its vertical axis. After the thread leaves the thread-guiding tube 71 it passes to the usual tension 76 and thence in usual way to one of the loopers.

While I have illustrated herein a selected embodiment of the invention I do not wish to be limited to the constructional features shown.

I claim:

1. In a sewing machine, the combination with a needle, of a sewing shaft by which the needle is operated, a turret, a looper carrier pivotally mounted on the turret, two loopers mounted on said looper carrier, loop spreaders also mounted on said carrier, a spreader actuator carried by the turret, and a cam device situated beneath the turret for oscillating the looper carrier and the spreader actuator.

2. In a sewing machine, the combination with a needle, of a sewing shaft by which

the needle is operated, a turret, a looper carrier pivotally mounted on the turret, two loopers mounted on said looper carrier, loop spreaders also mounted on said carrier, a spreader actuator carried by the turret, a cam device situated beneath the turret for oscillating the looper carrier and the spreader actuator, and operative connections from the cam to both the looper carrier and spreader actuator.

3. In a sewing machine, the combination with a needle, of a sewing shaft by which the needle is operated, a turret, a looper carrier pivotally mounted thereon, loopers and loop spreaders on the looper carrier, a spreader actuator, a cam device situated beneath the turret and geared to the sewing shaft, said cam having two cam grooves, operative connections between one cam groove and the looper carrier, and other operative connections between the other cam groove and the spreader actuator.

4. In a sewing machine, the combination with a needle, of a sewing shaft by which the needle is operated, a turret turnable about a vertical axis, oscillating loopers mounted on the turret, a cam device situated beneath the turret, gearing connecting said cam with the sewing shaft, a pivoted cam-actuated arm, and connections between said arm and loopers by which the latter are oscillated, said connections permitting turning movement of the turret.

5. In a sewing machine, the combination with a needle, of a sewing shaft by which the needle is operated, a turret turnable about a vertical axis, oscillating loopers mounted on said turret, loop spreaders co-operating with the loopers, a cam device situated beneath the turret, gearing connecting said cam device with the sewing shaft, two pivoted arms both actuated by said cam device, operative connections between one of said arms and the loopers, and means for actuating the loop spreaders from the other arm.

6. In a sewing machine, the combination with a needle operating from above the work, of a sewing shaft from which the needle is operated, a turret situated beneath the work and turnable about a vertical axis, oscillating loopers mounted on the turret, loop spreaders co-operating with the loopers, a spreader actuator, a cam device situated beneath the turret, two pivoted arms actuated by said cam device, and operative connections between one arm and the loopers and operative connections between the other arm and the spreader actuator.

7. In a sewing machine, the combination with a needle operating from above the work, of a sewing shaft by which the needle is actuated, a turret situated beneath the work, a looper carrier mounted on the turret, loopers on said looper carrier, loop spread-

ers co-operating with the loopers, an oscillating spreader actuator also carried by the turret, a cam device beneath the turret having two cam paths, two pivoted arms, one actuated by each path, a link connecting one arm to the looper carrier, and a link connecting the other arm to the spreader actuator, each link having a ball and socket connection with its arm situated in the axial line of the turret.

In testimony whereof, I have signed my name to this specification.

JOHN KIEWICZ.
